UNITED STATES PATENT OFFICE

167,160

CHAIN FOR A WRISTBAND OR SIMILAR ARTICLE

Alfred Pinson, Stamford, Conn., assignor to Apex Accessories Co., Inc., Greenwich, Conn.

Application November 1, 1951, Serial No. 17,226

Term of patent 14 years

(Cl. D45—4)

To all whom it may concern:

Be it known that I, Alfred Pinson, a citizen of the United States, residing at Stamford, in Fairfield County, State of Connecticut, have invented a new, original, and ornamental Design for a Chain for a Wristband or Similar Article, of which the following is a specification, reference being had to the accompanying drawing, forming part thereof.

I claim:

The ornamental design for a chain for a wristband or similar article, as shown.

ALFRED PINSON.
